UNITED STATES PATENT OFFICE

FRED PICKEL AND WILLIAM VON POELGEEST, OF NORTH BERGEN, NEW JERSEY

WINDOW SASH CONSTRUCTION

Application filed February 18, 1931. Serial No. 516,551.

This invention relates to double hung windows in which inner and outer sashes are slidably engaged in a grooved frame.

The conventional type of such windows 5 presents considerable difficulty in cleaning the glass carried by the sashes, due to the inaccessibility of their outer surfaces and danger encountered in attempts at cleaning, all of which is well known and many attempts have 10 been made to ameliorate these conditions.

With the foregoing in view, it has been an object of the present invention to provide a window with sashes so hung on an upright pivot member as to permit of being swung inwardly at their edges from the window frame, permitting full and easy access to both sides 15 of the panes from the inside of the building.

A further feature is in the provision of simple but highly efficient and easily operated means for supporting the sashes in whatever position they may be adjusted.

Another aim is to dispense with the usual counter balancing weights at one side of the window.

25 These advantageous objects and others of analogous nature as will hereafter appear, are attained by the novel construction and combination of parts as hereinafter described and illustrated in the accompanying drawings, constituting a component of this disclosure, and in which:

Fig. 1 is a front elevational view of a window constructed in accordance with the invention.

35 Fig. 2 is a transverse sectional view of the same drawn to an enlarged scale, showing the sashes as swung partially inward.

Fig. 3 is a similar view of the same but showing the sashes in closed, normal position.

40 Fig. 4 is a further enlarged sectional view showing the sashes and attaching members.

Fig. 5 is a similar view showing the opposite side of the sash frame and removable parting strips.

45 Fig. 6 is a top plan view of a modified form of support for the upright rail as extended.

Fig. 7 is a plan view of the parts shown in Fig. 6, in a closed position.

50 The window sash frame, shown in Fig. 1, may be in all respects of conventional con-

struction, consisting of right and left stiles 10-11, connected at the top by a crosspiece 12 and having at the bottom a sill 13, the usual moldings being used for ornamental effect.

The frame is also provided with boxes in 55 their outer portions to receive counter-balancing weights 14-15 for front and rear sashes respectively 16-17, normally slidable in grooved channels directly in register with the weight guiding boxes.

Set rigidly in the window frame, adjacent the side 10, are upright guide rods 18-19, disposed closely against the front sides of the sashes 16-17, and slidable on these rods are 60 brackets 20, 21 fixed on the upper and lower elements of the sashes, the edges of the sashes being shaped to permit of rotation without interference of adjacent parts.

The extreme left hand edge of each sash is 65 adapted to engage a flexible connection, as cord or chain, trained over pulleys, not shown, in the upper part of the window frame and engage the weights 14-15 in the usual manner, but no cords or weights are used on the opposite, right hand side of the sashes.

70 Due to the considerable length of the sash guide rods 18-19, a support or stay 22 is engaged by a hinge 23 to the frame member 10, at a point sufficiently above the top of the inner sash 16, to permit the sash to be raised 75 clear of the window sill 13, see Fig. 1.

The stay 22 is provided at its inner edge with notches adapted to partially encircle and effectively support the rods 18-19, as 80 best seen in Fig. 4, and its free end is formed 85 into a pad 24 to contact a fixed block 25 on the rear or outer element of the frame.

A catch 26, rotatable in the block 25, extends through a slot in the pad 24 and may 90 be turned to lockingly engage the end of the stay whenever desired, as for instance, when the sashes are turned inwardly on the axes of the rods 18-19.

95 When the sashes are in normal closed position and it is desired to adjust their height, the stay is released and turned inwardly on its hinge.

In the modification, seen in Figs. 6 and 7, a thin casing 27 is secured on the window frame member 10, and slidable in the casing is a 100

stay 22' having a pad 24' at its end and provided with notches to engage the rods in the foregoing manner, this stay being hinged to a runner 28 slidable in the casing 27.

5 The last named device practically conceals the stay when entered and may be preferred by reason of its unobtrusive appearance.

It is to be noted that the pivot rods 18-19 are in register with the parting strips of the 10 frame at the left hand side, while the corresponding parting strips 30-31 on the right hand side terminate at a point opposite the stay 22.

Continuations of the strips 30-31 are provided in the form of bars 32-33 having pins in their lower ends to engage in openings 34-35 in the window sill, and set in their upper portions are snap catches 36-37 manually operated and normally engageable in 20 keeper openings 38-39 in the bottoms of the fixed strips 30-31, as clearly shown in Fig. 5.

In operation, the inner sash is raised to clear the sill, and the outer sash is lowered to register with the inner sash. The stay 22 is secured in position to support the rods 18-19, the strip bar 32 is withdrawn and then the inner sash can be swung inwardly; thereafter the parting strip 33 is withdrawn and the outer sash may be turned inwardly, giving full access to each side of both 30 sashes in an obvious manner.

Though rigidly set, the guide rods 18-19 may be removed and replaced, should occasion arise, by merely rotating the rods 35 axially to unscrew them from the threaded sockets 40 in the sill and draw them downwardly from their loose confining sockets at the top of the frame.

It will be understood that the elements 40 may be repositioned and when so adjusted present the object of a common window.

Although we have described our improvements with considerable detail and with respect to certain particular forms of our invention, we do not desire to be limited to such details since many changes and modifications 45 may well be made without departing from the spirit and scope of our invention in its broadest aspect.

50 Having thus described our invention, what we claim as new and desire to secure by Letters Patent, is:

1. The combination with a double hung window having vertical rods adjacent one 55 side of the frame upon which the sashes are slidably hinged, of a removable stay for operatively engaging the rods to support them in substantially vertical alinement when the sashes are swung from the window frame, a slide to which the stay is hinged, and a socket enclosed within the trim of the frame receptive of said slide and stay for concealing the stay when not in use.

60 2. The combination with a double hung window having a pair of vertical rods adja-

cent one side of the frame upon each of which one of the sashes are slidably hinged, of a single removable stay for operatively engaging both the rods simultaneously to support them in substantially vertical alinement 70 when the sashes are swung from the frame, and means to conceal the stay when not in use.

3. In a double hung window, upright pivot rods removably arranged in the window 75 frame to extend from top to bottom thereof, one for each sash, slidable and rotatable connections between each sash and its corresponding rods, removable means on the opposite side of said frame normally confining 80 the sashes therein when in a lowered position, single individual weights for each sash operable in the frame adjacent said rods, and a single removable auxiliary support for both said rods midway their length.

4. In a double hung window, the combination of a casing, a pair of sashes operable therein, vertical rods fixed in said casing near one side thereof, each sash being hingedly and slidably connected to its corresponding rod, removable strips on the opposite side of said casing normally retaining said sashes in engagement, manual means for releasing and removing said strips, a stay hinged to said casing to engage both rods simultaneously, means for locking said stay when operatively adjusted, said stay permitting both sashes to turn inwardly therebelow, and a single weight for each sash on the side adjacent said rods.

5. In a double hung window, the combination of a casing, a pair of sashes operable therein, vertical rods removably engaged in said casing near one side thereof, each sash being hingedly and slidably connected to its corresponding rod, removable strips on the opposite side of said casing normally retaining said sashes in slidable engagement, means to retain said removable strips in adjustment, a stay hinged to said casing to engage and reinforce both rods simultaneously, means for locking said stay when operatively adjusted, and a single weight for each sash.

Signed at New York, in the county and State of New York, this 17th day of February, 1931.

FRED PICKEL
WILLIAM VON POELGEEST.
